UNITED STATES PATENT OFFICE.

ALBERT THOMPSON, OF PHILADELPHIA, PENNSYLVANIA.

LIFE-RAFT.

1,104,845.

Specification of Letters Patent. Patented July 28, 1914.

Application filed April 14, 1914. Serial No. 831,811.

To all whom it may concern:

Be it known that I, ALBERT THOMPSON, a citizen of the United States, and resident of Philadelphia, Pennsylvania, have invented 5 a new and useful Improvement in Life-Rafts, which invention is fully set forth in the following specification.

The present invention is an improvement in life rafts, particularly of the reversible and collapsible type shown in the patent to Ernest R. Greene, No. 1,089,338, dated March 3, 1914. In that patent there is disclosed valve mechanism for automatically venting the water from the raft in either of 15 its positions, but in order to insure the successful venting of the water with the device illustrated in the drawings of that patent, it is necessary to proportion the size of the flotative bodies with respect to the opening 20 or vent in the raft through which the water flows, and to make these bodies of such size that the buoyancy of the body in the raft will overcome the weight of the water in the raft and the suction of the water as it 25 passes through the opening or vent. This necessitates the employment of flotative bodies of relatively large size.

The objects of the present invention are to remove the necessity for proportioning the 30 size of the flotative bodies with respect to that of the opening or vent, and to provide a device of this character in which flotative bodies of practically any size may be employed with openings or vents of practically 35 any size, so long as the former will obturate the latter; to largely reduce the size of flotative bodies employed; to insure positive and certain operation of the device to automatically empty the raft; and to effect 40 these results by the employment of a simple and compact device that may be readily installed.

One embodiment of the inventive idea for securing these results comprises mechanism 45 (here shown as lever mechanism) for engaging and positively holding the flotative body in the raft away from its opening or vent, similar mechanism being associated with the other flotative body but being held out of engagement therewith.

The invention will be better understood by reference to the accompanying drawings, illustrating one expression of the inventive idea, and wherein—

55 Figure 1 is a longitudinal section through a reversible raft, showing a plurality of

venting devices; Fig. 2 is a transverse section on the line 2—2 of Fig. 1; Fig. 3 is a plan view of the casing of one of the venting devices; Fig. 4 is a vertical section 60 through one of the venting devices; Fig. 5 is a horizontal section on the line 5—5, Fig. 4; and Fig. 6 is a perspective view of the plate on which the valve seats are provided, and associated mechanism. 65

Referring to the drawings, wherein like reference numerals indicate like parts, any suitable reversible life raft may be employed, such as that disclosed in the Greene patent above mentioned. If desired, two 70 cylindrical buoyant members 7—7 may be used, the same being mounted on any suitable framework 8, and a suitable waterproof hull or body portion 9 is suspended from the structure in any desired manner. This 75 hull or body portion is open only at its top, and the bottom of said hull has secured thereto in any desired manner a body of buoyant material, such as a wooden plate 10 and cork bodies 11 and 12. This wooden 80 plate may be about one inch in thickness and each cork body may be three inches in thickness, in which event this bottom will have buoyancy sufficient to rise under the weight of a large body of water. When the 85 raft is in the position shown on Fig. 2, ropes 13 will pass under and support the hull, and when the parts are in reverse position, ropes 14 will perform this function.

Preferably the mechanism for automatically venting the raft is mounted on the bottom of the hull or body portion, and preferably at least three venting devices 15 are employed. As these devices are identical, a description of one will suffice. 90

Referring particularly to Fig. 4, 16 indicates any suitable flotative body, preferably of rubber and spherical in form, contained in a casing 17, and 18 is an identical flotative body contained in an identical casing 100 19, these casings being preferably secured together and to plate 10 by bolts 20 or other suitable means. A plate 21 is preferably held between these casings in any desired manner, and this plate is provided with a 105 vent or opening 22 and seats 23 and 24 for flotative bodies 16 and 18, respectively.

Means are provided for engaging and positively holding the flotative body 16 in the raft away from its seat and, inasmuch 110 as either flotative body 16 or 18 may chance to be the one in the raft, preferably identi-

cal means for each body are provided. As herein shown lever mechanism for this purpose, and preferably three levers 25 are pivoted on lugs 26 that may be formed integrally with plate 21. The inner ends of the levers associated with the flotative body in the raft engage and support the same, as shown in Fig. 4, and the outer ends of these levers are weighted in any suitable 10 or desired manner. As herein shown, a single circular weight 27 bears upon the ends of these levers, each of the latter projecting into recesses 28 in said weight, which recesses are preferably conical in 15 shape. The weight 27 is preferably guided in its movements in the casing 17, as by the provision of recesses 29 in the outer face of said weight engaging ribs 30 on the casing 17. The connections between the 20 casing 17, weight 27 and levers 25 are such as to prevent binding between the parts and to insure certainty in the movement of the levers 25 to hold the flotative body 16 away from its seat, so that the water in the raft, 25 which passes freely through perforations 31 in the casing 17, can also freely pass through the opening or vent 22. Until the level of the water in the raft and that of the supporting body of water are equalized, 30 or until the raft is emptied, the lower flotative body 18 will be held away from its seat 24. When the levels are equalized or when the raft is emptied, the pressure of the water outside of the raft will force the 35 body 18 into intimate engagement with seat 24 and hold it there until the level of the water in the raft is again higher than that of the supporting surface. In practice, the buoyancy of the bottom of the hull is such, 40 that after the levels are equalized (and if the weight of the passengers is removed—for example, if they sit on the framework 8), the bottom of the hull will rise under the weight of the water, thus maintaining 45 the level in the raft above that of the supporting surface until the raft is emptied.

The mechanism on both sides of plate 21 is, preferably, identical and, accordingly, as shown in Fig. 4, ring 27' acts to hold the 50 levers 25' out of engagement with flotative body 18. To further prevent levers 25' from interfering with body 18, the inner end of each of these levers engages one face 32' (Fig. 4) of a ridge provided on plate 55 21, the other face of which ridge constitutes seat 24. A ridge 32 is provided on the other face of plate 21, and corresponds to ridge 32'; lugs 26' correspond to lugs 26, recesses 29' with recesses 29, ribs 30' with 60 ribs 30, and perforations 31' with perforations 31.

Preferably the perforations 31 are so arranged in the casing 17 that, when the flotative body 16 is supported in the position 65 shown in Fig. 4, the moving water will

engage the body 16 below its center, thus assisting in maintaining the ball in the position indicated. In this position the water freely flows through perforations 31, opening or vent 22 and perforations 31'. 70

It is clear that, if the position of the parts shown in Fig. 4 were reversed, the same results would be attained.

While, for the purpose of illustration, one expression of the inventive idea has been shown and described in detail, it is to be understood that the invention is not limited to the construction shown, but that various embodiments may be had within the limits of the appended claims. It is to be further understood that the valve mechanism described may be used for other purposes than that herein disclosed. 75 80 85

What is claimed is:—

1. A reversible life raft provided with a 85 vent, two flotative bodies one on either side of said vent, means limiting the movement of said bodies with respect to said vent, and means engaging and holding the upper body away from said vent.

2. A reversible life raft provided with a 90 vent, two flotative bodies one on either side of said vent, means limiting the movement of said bodies with respect to said vent, and pivoted means engaging and holding the 95 upper body away from said vent.

3. A reversible life raft provided with a 100 vent, two flotative bodies one on either side of said vent, means limiting the movement of said bodies with respect to said vent, and weighted means engaging and holding the upper body away from said vent.

4. A reversible life raft provided with a 105 vent, two flotative bodies one on either side of said vent, means limiting the movement of said bodies with respect to said vent, and lever mechanism engaging and holding the upper body away from said vent.

5. A reversible life raft provided with a 110 vent, two flotative bodies one on either side of said vent, means limiting the movement of said bodies with respect to said vent, and weighted lever mechanism engaging and holding the upper body away from said vent.

6. A reversible life raft provided with a 115 vent, two flotative bodies one on either side of said vent, means limiting the movement of said bodies with respect to said vent, a plurality of levers engaging and holding the upper body away from said vent, and a 120 single weight bearing on said levers.

7. A reversible life raft provided with a 125 vent, two flotative bodies one on either side of said vent, a casing for each flotative body, a plurality of levers engaging and holding the upper body away from said vent, and a single weight bearing on said levers and provided with guide means engaging the walls of its casing.

8. A reversible life raft provided with a 130

5 vent, two flotative bodies one on either side of said vent, means limiting the movement of said bodies with respect to said vent, means engaging and holding the upper body away from said vent, and identical means associated with the other flotative body but being held out of engagement therewith.

10 9. A reversible life raft provided with a vent, two flotative bodies one on either side of said vent, means limiting the movement of said bodies with respect to said vent, pivoted means engaging and holding the upper body away from said vent, and identical means associated with the other flotative body but held out of engagement therewith.

15 10. A reversible life raft provided with a vent, two flotative bodies one on either side of said vent, means limiting the movement of said bodies with respect to said vent, weighted means engaging and holding the upper body away from said vent, and identical means associated with the other flotative body but held out of engagement therewith.

20 25 11. A reversible life raft provided with a vent, two flotative bodies one on either side of said vent, means limiting the movement of said bodies with respect to said vent, lever mechanism engaging and holding the upper body away from said vent, and identical lever mechanism associated with the other flotative body but held out of engagement therewith.

30 35 40 12. A reversible life raft provided with a vent, two flotative bodies one on either side of said vent, means limiting the movement of said bodies with respect to said vent, a plurality of levers engaging and holding the upper body away from said vent, a weight bearing on said levers, similar lever mechanism associated with the other flotative body, and a similar weight holding said levers out of engagement with said body.

45 50 55 13. A reversible life raft provided with a vent, two flotative bodies one on either side of said vent, a casing for each body provided with guiding means, a plurality of levers engaging the upper flotative body, a weight bearing on said levers and engaging said guiding means, a plurality of similar levers associated with the lower flotative body, and a similar weight holding said levers out of engagement with said body, said weight engaging the guiding means in its casing.

60 65 14. A reversible life raft having a buoyant bottom provided with a vent, two flotative bodies one on either side of said vent, means limiting the movement of said bodies with respect to said vent, means engaging and holding the upper body away from said vent, and identical means associated with the other flotative body but being held out of engagement therewith.

15 65 15. A reversible life raft having a buoyant bottom provided with a vent, two flota-

tive bodies one on either side of said vent, means limiting the movement of said bodies with respect to said vent, pivoted means engaging and holding the upper body away from said vent, and identical means associated with the other flotative body but held out of engagement therewith.

70 75 80 16. A reversible life raft having a buoyant bottom provided with a vent, two flotative bodies one on either side of said vent, means limiting the movement of said bodies with respect to said vent, weighted means engaging and holding the upper body away from said vent, and identical means associated with the other flotative body but held out of engagement therewith.

85 17. A reversible life raft having a buoyant bottom provided with a vent, two flotative bodies one on either side of said vent, means limiting the movement of said bodies with respect to said vent, lever mechanism engaging and holding the upper body away from said vent, and identical lever mechanism associated with the other flotative body but held out of engagement therewith.

90 95 100 18. A reversible life raft having a buoyant bottom provided with a vent, two flotative bodies one on either side of said vent, means limiting the movement of said bodies with respect to said vent, a plurality of levers engaging and holding the upper body away from said vent, a weight bearing on said levers, similar lever mechanism associated with the other flotative body, and a similar weight holding said levers out of engagement with said body.

105 110 115 120 19. A reversible life raft having a buoyant bottom provided with a vent, two flotative bodies one on either side of said vent, a casing for each body provided with guiding means, a plurality of levers engaging said upper flotative body, a weight bearing on said levers and engaging said guiding means, a plurality of similar levers associated with the lower flotative body, and a similar weight holding said levers out of engagement with said body, said weight engaging the guiding means in its casing.

20 25 20. A valve mechanism provided with a vent, two flotative bodies one on either side of said vent, means limiting the movement of said bodies with respect to said vent, and means engaging and holding the upper body away from said vent.

120 125 21. A valve mechanism provided with a vent, two flotative bodies one on either side of said vent, means limiting the movement of said bodies with respect to said vent and lever mechanism engaging and holding the upper body away from said vent.

22. A valve mechanism provided with a vent, two flotative bodies one on either side of said vent, means limiting the movement of said bodies with respect to said vent, means engaging and holding the upper body 130

away from said vent, and identical means associated with the other flotative body but held out of engagement therewith.

23. A valve mechanism provided with a vent, two flotative bodies one on either side of said vent, means limiting the movement of said bodies with respect to said vent, lever mechanism engaging and holding the upper body away from said vent, and identical lever mechanism associated with the other flotative body but held out of engagement therewith.

24. A valve mechanism provided with a vent, two flotative bodies one on either side of said vent, means limiting the movement of said bodies with respect to said vent, a lever mechanism engaging and holding the upper body away from said vent, a weight bearing on said lever mechanism, and identical lever mechanism associated with the other flotative body but held out of engagement therewith.

25. A valve mechanism provided with a vent, two flotative bodies one on either side of said vent, means limiting the movement of said bodies with respect to said vent, a

plurality of levers engaging and holding the upper body away from said vent, a weight bearing on said levers, similar lever mechanism associated with the other flotative body, and a similar weight holding said levers out of engagement with said body.

26. A valve mechanism provided with a vent, two flotative bodies one on either side of said vent, a casing for each body provided with guiding means, a plurality of levers engaging the upper flotative body, a weight bearing on said levers and engaging said guiding means, a plurality of similar levers associated with the lower flotative body, and a similar weight holding said levers out of engagement with said body, said weight engaging the guiding means in its casing.

In testimony whereof I have signed this specification in the presence of two subscribing witnesses.

ALBERT THOMPSON.
